KNUTE EDAHL, OF CHICAGO, ILLINOIS

DOORPOST AND SIDE-PLATE CONNECTION

Application filed February 27, 1930. Serial No. 431,679.

My invention relates to railroad freight cars and particularly to the door posts and side plate connections which involves a suitable door-track support; the connection member being also formed to provide proper weather protection at the door post; while at the same time providing a firm, rigid connection.

The objects and advantages of my invention will be readily comprehended from the following detailed description of the accompanying drawings, wherein:

Figure 1 is a side elevation of a portion of a car side wall and portion of a door, provided with my invention.

Figure 2 is a top plan view with a portion of the side plate broken away and shown in section.

Figure 3 is a sectional elevation taken substantially along the line 3—3 of Figure 1, as viewed by the arrows.

Figure 4 is a perspective view of my improved connection member and door track support.

Figure 5 is a sectional elevation taken substantially along the same line as Figure 3 but showing application to a car wall formed with double sheathing.

In the particular exemplification of the invention as shown in Figures 1 to 3, a portion of a car wall of single sheathing is shown at 10, provided with the side plate 11 which extends from end to end of the car above the door-openings; the plate 11 being a part of the car construction and constituting a compression member.

The side plate 11 is of Z-shape in cross-section and is suitably attached to a car side wall so as to have one leg or flange of the plate depend, in spaced relation with the car wall and across the top of the door-openings.

Secured to the car outer side wall and to the side plate 11 and slightly beyond what is termed the front end of the door, is my improved connection member or casting 12, shown in perspective in Figure 4.

This member 12 has a vertical rear wall 13, which is formed with an off-set as at 14; and a vertical end wall 15, formed integral with wall 13. The upper ends of these walls ter-

minate in the horizontally disposed flange 16, which, for the sake of lightness, may be made arcuate at the forward edge as shown in Figure 4. This top flange 16 and the outer edge of the end wall 15 are provided with the integral vertically disposed flange 17 which extends forwardly from the forward edge of the end wall. The flange 17, at a short distance from the bottom of the casting curves upwardly to provide the groove 18; and this upwardly curved or bent portion terminates in a horizontally and outwardly disposed flange portion 19, with one edge thereof also formed integral with the extension 20 of the end wall 15. The rear vertical wall 13 is shown provided with bolt-holes 21 and 22; the end wall 15 shown provided with bolt-holes 23; the top flange shown provided with bolt-holes 24; the vertical flange 17 shown provided with a bolt-hole 25; while the horizontal flange 19 is shown provided with a bolt-hole 26.

The rear wall 13 of the member 12 is intended to be secured to the outer car wall by means of the bolts 27, as shown in Figure 3; and this rear wall is off-set as shown at 14 so as to permit the member to lap the metallic door-post element 28, disposed vertically at the front end of the door-opening and of Z-shape in cross-section as shown more clearly in Figure 2.

By providing the member 12 with the off-set rear wall as shown, the outer end of the casting may fit flush with the car wall, forward of the door-post 28, while the major portion of the member is inlapping relation with the door post. The hole 22, in the rear wall 13 of the casting or member 12, receives the rivet 29, whereby the member is rigidly attached to the door-post 28. It is apparent that with this construction a weather-proof connection between the door-post and connection member 12 is provided. By forming the vertical flange 17 as shown and described, intimate weather-proof connection with the side plate 11 (which also is of Z-shape in cross-section) may be provided because the depending leg or side of the side-plate 11 fits into the groove 18 as shown in Figure 3; while the top side or flange 16 of the mem-

ber 12 fits against the lower face of the horizontally disposed portion of the side plate 11 and is riveted thereto by the rivets 30; while the depending leg or side of the side plate 11 is secured to the forward flange 17 by suitable rivet 31 which passes through the hole 25 of member 12.

The horizontally disposed flange portion 19 of member 12 provides a suitable support 10 for the end of door-track 32, which extends lengthwise of the car above the door opening and somewhat beyond the rear end of the door-opening as is usual in car construction. The door-track 32 is in the nature of a Z-bar, one side whereof is disposed vertically 15 flush with the outer face of the depending side of the side-plate 11.

The lower edge of the side plate, as previously stated, is seated in the groove 18 of member 12; and the door-track 32 is secured to member 12 and to the side-plate 11 by the same rivet 31, with the depending side of the track 32lapping the forward side of the member, all as shown more clearly in Figure 20 3. The end of the door-track 32 is also riveted to the horizontally disposed flange portion 19 by the rivet 33 which passes through the hole 26; this rivet being disposed beyond the usual door-hanger when the door is closed.

In Figure 5 I illustrate my improved door-post and side-plate connection applied to a car provided with a double wall, wherein the outer sheathing is shown at 34, which is made to practically fit into the connection 12^a 35 bylapping the inner face of the flange portion 17; the connection member 12^a being identical with member 12 previously described and being attached to the side plate 11 and to the door-track 32 which is supported at the end by member 12^a, all as previously described. Where the connection element is used on a double wall car, bolts 35 and 36 are used instead of the short bolts 27 and rivet 29; the long bolt 35 being made 40 to pass through the upstanding side of track member 32, through the depending side of the side plate 11 and a filler block or spacing member 37 which fits into member 12^a between the inner and outer walls of the member and therefore between the inner and outer sheathing of the car; while the long bolt 36 passes through the outer sheathing 34 and the rear wall 13 of member 12^a.

The connection member 12^a, like in the previous figures, laps the rear side of the Z-shaped metallic door-post member 28; while the horizontal flange portion 19 supports the end of the door-track 32 which is riveted to the member as previously stated.

It will be understood that the metallic door-post member 28, at the forward end of the door-opening, receives the usual wood post or filler member 38; while the upper end of the door, partly shown at 39, is provided with the usual roller-hangers (not

shown) which ride on the track member 32.

The metallic door post member 28 is provided with the usual door-stop 40 (shown in dotted lines in Figure 2) riveted thereto as shown at 41; the free longitudinal edge of 70 the stop 40 being offset outwardly to receive the Z-bar or flanged metallic bar 42 secured to the forward end of the door 39, see Figure 2.

With my improved door post and side plate 75 connection, these elements are not only rigidly connected together and reenforced so as to anchor the tortional forces or stresses to the side plate and a suitable support for the door-track provided, but the openings 80 between the side-plate and the door-post, and the openings about the door and the door-track, are all closed and weather-proof connection provided.

Furthermore, with my improved connection, 85 openings between the inside lining and the door-post in a single sheathed car are closed; while at the same time providing means to which the lining boards may be secured; and again providing means for securing the side plate filler of a double sheathed car.

My improved connection member, as shown in the drawings, is applicable to both single and double sheathed cars having the same 95 kind of door track, without change in the casting; and with my improved element a more rigid and stronger car construction is provided, adapted to withstand the severe 100 strains and shocks encountered in freight cars and freight car door operation; while at the same time providing closure for the openings, necessarily occurring between the various elements at the forward end of the door, against ingress of rain or moisture.

I have shown what is believed to be a simple embodiment of the invention which has been described in terms employed merely as terms of description and not as terms of limitation, as structural modifications may be made without, however, departing from the spirit of my invention.

What I claim is:

1. In combination with the side-plate and door-post of a freight car; a connection member comprising a metallic element having a vertical rear wall adapted to lap one longitudinal side of the door-post, a top wall adapted to extend flush with and to be secured to the lower face of the side-plate, while the forward side of said element is provided with a groove to receive the depending outer longitudinal side of the side-plate.

2. In a railroad car provided with a Z-shaped side-plate, a Z-shaped door-post and a track-rail; a connection member provided with a vertical rear wall formed to be secured to the car wall and to lap the inner longitudinal side of the door-post and be secured thereto, said member having a top wall adapted

to extend flush with and be secured to the intermediate portion of the side-plate; the forward portion of the member being provided with a vertical portion bent upwardly and outwardly adjacent to the lower end to receive the outer vertical side of the side-plate, while the outwardly disposed portion is adapted to support the track-rail.

3. In a railroad car provided with a Z-shaped side-plate, a Z-shaped door-post and a track-rail; a connection member provided with a vertical rear wall having an off-set to adapt one portion of said wall to lie flush with the car side wall while the other portion laps the inner side of the door-post and is secured thereto; said member having a top wall adapted to extend flush with and be secured to the intermediate portion of the side-plate; said member also having at front a vertically disposed portion bent upwardly and outwardly adjacent to the lower end to provide a groove for the depending outer side of the side-plate and to provide a support for the track-rail.

25. 4. A connection member of the character described comprising a single piece member provided with a vertical rear wall, an end wall and a top wall; the end wall terminating in a laterally disposed portion bent upwardly and outwardly to form a socket between the main laterally disposed portion and the upwardly and outwardly bent portion; said walls and portions having bolt receiving openings.

35. 5. In a railroad freight car provided with a Z-shaped side-plate, a Z-shaped door-post and a Z-shaped track-rail; a connection member having a rear wall adapted to be connected to the car wall and to lap the rear longitudinal side of the door-post; an end wall adapted to extend flush with and be secured to the intermediate portion of the door-post; a top wall adapted to be secured to the intermediate portion of the side-plate; and a laterally disposed flange at the forward edge of the end wall to extend flush with and be secured to the depending side of the side-plate; the end wall and said flange curving upwardly at the lower end to lap the forward side of the side-plate and to provide a support for the track-rail.

6. In a railroad freight car, an angular side-plate, an angular door-post, an angular track-rail, and a single piece connection member provided with a vertical rear wall, adapted to extend flush with the car wall and to lap one longitudinal side of the door-post; an end wall adapted to extend flush with the intermediate part of the door-post; a top wall adapted to extend flush with and be secured to the lower face of the intermediate portion of the side-plate; the forward vertical edge of the end wall terminating in a laterally disposed portion adapted to extend flush with the inner face of the outer depending portion

of the side-plate; the lower part of the end wall being extended forwardly of said laterally disposed portion and formed to provide a socket for the depending portion of the side-plate and to provide a horizontal support for the track-rail.

7. In a railroad freight car, the combination of a side-plate, angular in cross-section; a door-post, angular in cross-section, and a track-rail; with a connection member adapted to lap the rear side of the door-post in weather-proof relation with the car wall and to extend flush with and be secured to said rear side and the intermediate portion of the door-post and to extend flush and be secured to the lower face of the intermediate portion of the side-plate and to extend flush with the rear face of the depending portion of the side-plate; with the forward face of said connection member provided with a vertically disposed groove to receive the depending portion of the side-plate; said forward portion of said member terminating in a laterally disposed face adapted to receive the track-rail; all of said elements being rigidly secured to said member.
